United States Patent Office.

BAKER VAN AUSDALL, OF KEOKUK, IOWA.

Letters Patent No. 80,087, dated July 14, 1868; antedated July 6, 1868.

IMPROVEMENT IN BOOT-SOLES.

The Schedule referred to in these Letters Patent and making part of the same.

TO ALL WHOM IT MAY CONCERN:

Be it known that I, BAKER VAN AUSDALL, of Keokuk, in the county of Lee, and State of Iowa, have invented a new and useful Improvement in Soles for Boots and Shoes; and I do hereby declare that the following is a full, clear, and exact description thereof, which will enable those skilled in the art to make and use the same, reference being had to the accompanying plate of drawings, and to the letters of reference marked thereon, forming part of this specification.

The present invention consists in making the outside or wearing-sole of a boot or shoe of wood, and in a series of sections or parts, from the ball of the foot to the back of the heel, whereby a flexible sole is obtained.

In the accompanying plate of drawings my improvement in boot and shoe-soles is illustrated—

Figure 1 being a view of the under or treading-surface to a boot provided with my improved sole.

Figure 2, a section taken in the plane of the line x x , fig. 1.

Similar letters of reference indicate corresponding parts.

A, in the drawings, represents a boot or shoe, made with a wooden sole, B, applied to the outside of the ordinary leather sole, and made in sections or parts C, from the toe of the sole to the heel.

Having thus described my invention, I claim as new, and desire to secure by Letters Patent—

As a new article of manufacture, a flexible wooden boot-sole and heel, formed of independent sections of wood riveted to the leather inner sole, as herein described, for the purpose specified.

The above specification of my invention signed by me, this seventeenth day of September, 1867.

BAKER VAN AUSDALL.
